CLAIM

The ornamental design for a sword blade, as shown and described.

DESCRIPTION

FIG. 1 is a left side elevational view of a sword blade with the sword handle depicted in phantom lines which forms no part of the claimed design for this invention, the right, opposite, side of which is a mirror image thereof; FIG. 2 is a front elevational view of the sword blade of FIG. 1;

FIG. 3 is a rear elevational view of the sword blade of FIG. 1;

FIG. 4 is a top plan view of the sword blade of FIG. 1, of which the bottom plan view is a mirror image thereof; and, FIG. 5 is a left side elevational view of an alternative embodiment of the sword blade with the sword handle depicted in phantom lines which forms no part of the claimed design for this invention.

The broken lines shown are for illustrative purposes only and form no part of the claimed design.
